Attest.

UNITED STATES PATENT OFFICE.

WILLIAM STUART TAIT, OF CLEVELAND, OHIO, ASSIGNOR TO THE HYDRAULIC
PRESSED STEEL COMPANY, OF CLEVELAND, OHIO, A CORPORATION OF OHIO.

JOIST-BRACKET.

1,398,579.

Specification of Letters Patent. Patented Nov. 29, 1921.

Application filed November 21, 1919. Serial No. 339,746.

To all whom it may concern:

Be it known that I, WILLIAM STUART TAIT, a citizen of the United States, residing at Cleveland, in the county of Cuyahoga and 5 State of Ohio, have invented a certain new and useful Improvement in Joist-Brackets, of which the following is a full, clear, and exact description, reference being had to the accompanying drawings.

10 This invention is a novel construction of joist brackets adapted to be used in connection with supports for concrete forms, the object of invention being to provide a bracket capable of holding and supporting 15 joist ends, said bracket being of such construction that the joist ends can be placed thereon at different times without dislocating the bracket or any part thereof. The invention consists in the details of construction hereinafter fully described and pointed 20 out in the claims.

In the drawings forming a part of this specification Figure 1 is a perspective view of a joist receiving member; Fig. 2 is a 25 detail perspective view of a strap for locking the same; Fig. 3 is a view showing the practical application of the device; and Fig. 4 is a sectional elevation on the line 4-4 of Fig. 3.

30 In carrying out my invention I employ a channeled joist receiving member A formed of sheet metal and dimensioned according to the size of joists to be employed in connection therewith. To the bottom of this mem-

35 ber at each end thereof is attached a right angled strap B, the depending leg of which is bowed outwardly as shown at B'. In connection with each right angled strap B I employ an L-shaped strap C, the vertical 40 member of which is slotted and looped as shown, said slotted and looped portion of the strap C being adapted to be brought into registering engagement with the bowed portion B' of the strap B and locked by means 45 of a locking wedge D. In operation the bracket A is rested upon stringers E and the locking straps C are hooked under said

stringers and the looped portions thereof locked to the lower ends of the straps B as previously described. The ends of the joists 50 F and G can then be rested upon and within the bracket A and inasmuch as said bracket is securely locked against tilting movement in either direction it is obvious that either of the joists can be placed first upon the 55 bracket.

Heretofore, so far as I am aware, it has been necessary to place the joists simultaneously upon any bracket or connecting support in order to avoid tilting. 60

The device herein shown is made entirely of sheet metal and is quickly and easily manipulated either in setting up or taking down as it is obvious that it is only necessary to bring the parts into proper relation and 65 insert the wedge in order to assemble the parts properly and that it is only necessary to remove the wedge in order to disconnect the parts.

Having thus described my invention, what 70 I claim is:—

1. In a device of the kind described, the combination with a joist receiving member, of straps depending therefrom and having each a bowed portion, and straps adapted to 75 engage the under side of stringers and having each a bowed portion, said bowed portions coöperating to define an opening, and means positioned in said opening for detachably connecting said first and last named 80 straps.

2. In a device of the kind described, the combination with a channeled joist receiving member, of depending straps connected thereto, the lower ends of which are bowed, 85 and L-shaped straps having their upper ends slotted and looped, said bowed portions and said slotted and looped portion defining openings, and locking wedges adapted to be inserted in said openings thereby to connect 90 said depending and L-shaped straps.

In testimony whereof, I hereunto affix my signature.

WILLIAM STUART TAIT.
